His Attorney.

UNITED STATES PATENT OFFICE

2,299,575

TUYÈRE

Charles J. Fleisch, Pittsburgh, Pa.

Application May 23, 1940, Serial No. 336,803

3 Claims. (Cl. 122—6.6)

This invention relates to improvements in tuyères for blast furnaces and the like, and more particularly relates to a water-cooled tuyère having a protective refractory back.

Blast furnace tuyères may become burned in use, and when such failure occurs, the present water-cooled tuyères become dangerous to the operators and equipment. The water must be shut off to prevent discharge thereof into the furnace, whereupon the unprotected tuyère burns through and permits burning of the blowpipe and cooler parts, frequently resulting in what is known as a "blow-out," whereby hot slag, coke, etc., are discharged through the damaged tuyère assembly.

My invention contemplates the provision of a protected tuyère which will prevent such hazards and insure greater safety to operators and equipment.

Another object is to provide more efficient cooling for the tuyère by localization of the applied cooling medium, and at the same time, reducing the cooling effect of the tuyère upon the hot blast delivered thereby, resulting in a saving of fuel.

Additional objects and advantages will become apparent from the following description taken in connection with the accompanying drawing, wherein:

Figure 1 is a detail sectional view through the tuyère section of a blast furnace showing my improved tuyère mounted therein;

Figure 2 is an enlarged rear elevational view of the tuyère;

Figure 3 is a cross section on the line III—III of Figure 2;

Figure 4 is a cross section on the line IV—IV of Figure 3;

Figure 5 is a rear elevational view of a modified form of tuyère; and,

Figure 6 is a sectional view on the line VI—VI of Figure 5.

Referring to the drawing, Figure 1 shows one form of my improved tuyère A positioned in a blast furnace wall 5 in the customary mounting, including a cooler 6. Said tuyère and cooler are generally of frusto-conical shape and have coacting seating portions for positioning and retaining the tuyère in the furnace.

As shown in Figures 2 to 4, the tuyère A preferably comprises a double-walled annular body or shell of copper or other metal, having a central longitudinal blast passage 7 therethrough. The forward or nose portion of the tuyère which extends into the furnace is provided with an annu-

lar water-jacket 8 surrounding the forward portion of the blast passage 7. 9 designates a transverse partition wall defining the rearward extent of the water-jacket 8.

5 The rear portion of the tuyère A is provided with an external annular seating portion 10 for fitting sealing engagement with the cooler 6 as stated, and the rear wall 11 of the tuyère is formed with a tapered seat 12 surrounding the 10 rear end of the passage 7 for seating the terminal of the hot blast blowpipe 13 as in Figure 1, said blowpipe supplying the heated air for the furnace from the usual source.

Surrounding the rear portion of the passage 7 15 and extending forwardly to the partition wall 9, I provide a refractory portion, preferably in the form of a refractory-containing jacket 14, utilizing the space between the walls of the shell or body in the region stated. Said refractory jacket

20 is disposed in protective relation to the rear wall of the tuyère and the annular seat 10, and preferably extends longitudinally throughout at least one-half of the longitudinal length of the tuyère, the extent thereof being controlled by the location of the partition wall 9.

A powdered or granular refractory *a* may be employed for filling the refractory jacket 14 through provided access openings 15 in the rear wall of the tuyère, the openings being closed by 25 threaded plugs or the like after filling.

In the form of Figures 2 to 4, openings 16 are provided in the rear wall of the tuyère communicating with provided longitudinal channels or passages 17 formed integrally with the tuyère 30 body and extending through the refractory jacket for water circulation to and from the water-jacket 8 through communicating openings 18 in the partition wall 9.

In the modification shown in Figures 5 and 6, 40 the tuyère A' is like that previously described excepting for the provision of a rear wall comprising openings and integral ribs, whereby a plastic refractory may be applied to the refractory jacket 14. In this form, the water circulation for the 45 water-jacket 8 is provided by a pair of conduits 20 extending from said rear wall through the partition wall 9.

From the foregoing it is apparent that I have provided a tuyère having a refractory jacket 50 which serves to protect the rear portion of the tuyère even in the event the water-jacket burns and fails, the protection afforded by the refractory portion being maintained irrespective of whether the cooling water is shut off or not. The location of the refractory jacket at the rear por-

tion of the tuyère adequately protects the juncture with the cooler 6 and the blowpipe 13, preventing the latter from being burned. Also, by maintaining the juncture with the cooler, slag, etc., will not be discharged or blown out therebetween.

Further, by reducing the extent of the water-jacket, I have concentrated the cooling circulation of water at the region where the same is most effective and essential. Also, the reduced cooling area has a correspondingly reduced cooling effect upon the hot blast delivered by the tuyère.

Various modifications and changes are contemplated within the scope of the following claims.

I claim:

1. A tuyère comprising a hollow body having a central longitudinal passage therethrough and having a rear outer seating portion, a water-cooled nose portion surrounding the forward portion only of said passage, a protective refractory portion surrounding the rear portion of the passage, said refractory portion extending rearwardly from and isolating the water-cooled nose, and protecting the seating portion of the tuyère and the tuyère body in the event of burning of the nose.

2. A tuyère comprising a hollow body having a central longitudinal passage therethrough and having a rear outer seating portion, a water-

cooled nose portion surrounding the forward portion only of said passage, a protective refractory portion surrounding the rear remaining portion of the passage, said refractory portion extending longitudinally throughout at least one-half of the longitudinal dimension of the tuyère, isolating the water cooled nose and protecting the seating portion of the tuyère and the tuyere body in the event of burning of the nose.

10 3. A tuyère comprising a double-walled annular metal body having a central longitudinal blast passage therethrough and having a rear outer seating portion, the forward portion of the double-walled body about said passage comprising a

15 water-jacket forming a water-cooled nose, a partition wall defining the rearward extent of said water-jacket, refractory filling the remainder of the space between the walls of the body and forming a refractory portion surrounding the rear

20 portion of the passage, isolating said water-cooled nose and protecting the seating portion of the tuyère and the tuyère body in the event of burning of the nose, said body having access openings in the rear thereof for introducing the

25 refractory material thereto, and water conduits extending from said partition wall to the rear of the body and in communication with said water-jacket.

CHARLES J. FLEISCH.
